UNITED STATES PATENT OFFICE.

CHARLES DARWIN BINGHAM, OF WATERTOWN, NEW YORK, ASSIGNOR TO
PRENTISS VISE COMPANY, OF NEW YORK, N. Y.

VISE.

SPECIFICATION forming part of Letters Patent No. 703,378, dated July 1, 1902.

Application filed February 7, 1902. Serial No. 93,068. (No model.)

To all whom it may concern:

Be it known that I, CHARLES DARWIN BINGHAM, of Watertown, in the county of Jefferson and State of New York, have invented a new and useful Improvement in Vises, of which the following is a specification.

My improvement relates to what are known as "parallel-jaw bench-vises." Its object is to strengthen the vise and to enable it to more effectively resist tensional strain without enhancing the expense of construction.

I will first describe by reference to the accompanying drawings the manner in which my invention is carried into effect and will then point out more particularly in the claim those features which I believe to be new and of my own invention.

In the drawings, Figure 1 is a longitudinal central section of a machinist's vise embodying my invention. Fig. 2 is a bottom plan of the movable jaw detached. Fig. 3 is a front elevation of the movable jaw. Fig. 4 is a rear elevation of the back jaw or body of the vise.

A is the cast-iron back jaw or body of the vise, which is what is known as a "parallel-jaw bench-vise." To it is fixed the nut B, which is engaged by the vise-screw E of the movable jaw.

C is the head of the movable jaw. D is its shank, made of wrought iron or steel and having the form of a tubular cylinder. In practice I make it out of the regular gas-pipe of commerce, which is comparatively cheap and can be had in a sufficient variety of sizes and thicknesses to make it available for any desired range in sizes of vises. The head C is cast upon the exterior of the wrought-metal cylindrical tubular slide or shank D, the two being united by and during the operation of casting the head C, and the shank D is then longitudinally slotted, as at d, to permit it to straddle the neck b of the nut B, which is housed in the shank and engages the screw E, as shown. The cast-iron of the head C is stopped out of or excluded from the interior of shank D. If admitted thereto, it would perform no useful office, because in cooling it would shrink and draw away from the interior surface of the pipe. By omitting it there is less boring and cutting of the head for the passage of the screw, and I am also enabled to

provide within the compass of the head a chamber f, which may be utilized for a variety of purposes. In the present instance it contains the collar e, by which the screw E is swiveled in the head. This collar after the screw is inserted through the hole bored for it in the comparatively thin front wall of the head is slipped on the stem of the screw to the position shown in Fig. 1 and is there secured to the shank by a set-screw e', which can be reached through a hole e² in the head C and pipe D. The vise thus made is exceedingly strong, durable, and efficient, the cost of construction is not enhanced, the screw is completely housed and protected, and the defects incident to prior constructions, whether cast-iron or wrought-iron, are done away with.

With very few exceptions all parallel-jaw bench-vises, so far as I am informed, are made of cast-iron and possess the defects incident to that material, which is strong in compression, but comparatively weak in tension. The strain which tends to break such vices is in most cases that which tends to hold the jaws apart against the pressure of the screw. This strain is greatest directly underneath the opposed faces of the jaws, and the breakage usually occurs at approximately that point in the cast-iron shank, whether it be solid or hollow. To obviate this serious objection, attempts have been made heretofore to replace in such vises the cast-iron shank by a shank of wrought iron or steel. The shank in this case when tubular, or rather semitubular, has been made of a wrought iron or steel "channel-bar;" but such a shank has been objectionable and unsatisfactory for the reason, among others, that the intense heat to which it or a portion of it is subjected in the operation of casting and molding the cast-iron jaw upon it tends to materially put it out of shape and distort it out of true to such an extent as to make it useless until restored to its original and proper shape, which latter cannot be done except at a cost which is practically prohibitory; but by giving the wrought-metal shank a tubular cylindrical form these objections are to a very great extent, if not entirely, removed. The wrought metal is put into the best shape possible to resist any tendency to distortion due to the

casting operation and to effectively maintain its original shape. The wrought-metal tube of course is, as hereinbefore stated, left intact until after the cast-iron head of the jaw 5 is fully completed. The longitudinal slot *d* in the under side of the tube is then milled; but the tube not being afterward exposed to heat is not distorted, but retains its original shape.

10 What I claim herein as new, and desire to secure by Letters Patent, is as follows:

In a vise a sliding jaw composed of a cast-iron head a wrought-metal pipe-shank united with the cast-iron head by and during the

casting operation, and longitudinally slotted 15 for the passage of the neck of the feed-nut on the stationary jaw or vise-body, and a screw to engage said nut swiveled in the front wall of the cast-metal head and housed in the wrought-metal pipe-shank, as and for the 20 purposes hereinbefore set forth.

In testimony whereof I have hereunto set my hand this 1st day of February, 1902.

CHARLES DARWIN BINGHAM.
